UNITED STATES PATENT OFFICE

148,611

DESIGN FOR A SHADOW BOX MIRROR

Joseph Friedman, New York, N. Y.

Application September 7, 1946, Serial No. 133,134

Term of patent 3½ years

(Cl. D33—9)

To the Commissioner of Patents:

Be it known that I, Joseph Friedman, a citizen of the United States, residing at New York, in the county of the Bronx and State of New York, have invented a new, original, and ornamental Design for a Shadow Box Mirror, of which the following is a specification, reference being had to the accompanying drawing, forming part thereof.

Fig. 1 is a front view of a shadow box mirror, showing my new design.

Fig. 2 is a fragmentary edge elevational view looking in the direction of the line 2—2 of Fig. 1.

I claim:

The ornamental design for a shadow box mirror, as shown.

JOSEPH FRIEDMAN.
